UNITED STATES PATENT OFFICE.

WILLIAM WILEY PLOWMAN, OF CAMARGO, ILLINOIS.

METALLIC TIE.

1,296,425.

Specification of Letters Patent.

Patented Mar. 4, 1919.

Application filed October 13, 1916, Serial No. 125,470. Renewed August 3, 1918. Serial No. 248,226.

To all whom it may concern:

Be it known that I, WILLIAM W. PLOWMAN, a citizen of the United States, residing at Camargo, in the county of Douglas 5 and State of Illinois, have invented new and useful Improvements in Metallic Ties, of which the following is a specification.

The present invention relates to metallic ties and rail fasteners associated therewith, 10 and one of the primary objects of the invention is to construct a tie for supporting rails that can be tamped and firmly anchored in the roadbed.

Another object of the invention is to provide 15 a metal tie having integral rail engaging members which engage with the outer edges of the rail flanges, whereby the rails may be properly spaced by such contact and thus materially facilitate the laying of the 20 rails.

A further object of the invention is to provide 25 a metal tie which has integral rail engaging means associated therewith adjacent its ends and removable and adjustable rail fasteners disposed adjacent the said rail engaging means, the securing element for the fasteners being so arranged as to permit of the fasteners being adjusted from the ends of the tie and consequently from the exterior 30 of the track, thus obviating the liability of danger to the track hand working between the rails of a track.

With the above and other objects in view, the improvement resides in the construction, 35 combination and arrangement of parts set forth in the following specification and falling within the scope of the appended claim.

In the drawing:

Figure 1 is a perspective view of a tie and 40 rail fastener constructed in accordance with the present invention,

Fig. 2 is a side elevation of a portion of the tie,

Fig. 3 is an end elevation of the same, 45 Fig. 4 is an enlarged central longitudinal sectional view taken approximately on the line 4-4 of Fig. 3, and

Fig. 5 is a perspective view of one of the rail fasteners.

The roadbed within which ties constructed 50 in accordance with my invention are adapted to be laid may be, and preferably is, formed of concrete, and each of the ties includes a flat base 1 which is adapted to be received in the said concrete and from which projects the substantially rectangular tie

proper 2. The tie has upwardly converging sides and the ends thereof project at the bottom of the tie. The tie, at its ends, and upon its upper face, is integrally formed with rail engaging members 4, the inner faces of the same being cut away and shaped to snugly receive the outer flanges of the rails 3. The seats 5 for the rails 3 are disposed opposite the rail engaging members or lips 4 and are, of course, horizontally flat and the said seats are of a width equal only to the width of the base flanges of the rails. The tie top is provided adjacent the rail seats with transverse dove-tailed recesses 6. The rail clamp members are indicated by the numerals 11 and include each a dove-tailed base 10, the angular ends of which being designed to engage with the angular end walls 7 and 8 of the recess 6. Integrally formed at one of the corners of the body 10 is a rail engaging extension 13, the under surface of which being inclined, as at 14, to conform to and to engage with the angular upper face of the foot of the rail 3, on the inner side of the said rail. The rail engaging extension is also designed to contact with the edge of the foot of the rail, and the said extension, at its juncture with the body 10 is formed with an angularly arranged opening that is designed to align with a similar opening 16 between the walls 8 and the ends of the tie. The shanks 17 of headed elements 18 pass through the registering openings 15 and 16, the ends of the shanks being threaded and projecting over the ends of the body of the tie proper. The bolt members have their shanks 17, when received in the openings between the clamp plates and the tie, arranged to contact with the inner corners of the foot or base portions of the rails 3, the angular arrangement of the said bolts being also desirable, inasmuch as the same tends to force the rail engaging extensions of the clamping plates downwardly on the rails 3 as well as bringing the clamping plates toward the rails and the angular inner walls 14 of the extension 13 into tight contact with the upper surfaces of the foot or base portions on the inner sides of the said rails, thus forcing the outer portions of the said foot or base flanges of the rails into tight engagement with the lips 4 of the ties 1. These threaded ends are engaged by nuts 19, suitable washers 20 being disposed between the nuts and the ends of the tie proper.

The seats 5 may be provided with compressible cushion members so that the yieldability of the rails 3 will not be interfered with, and the fastening members 11 can be 5 adjusted from the ends of the ties and consequently from the outer sides of the track, as will be readily understood.

From the above description, taken in connection with the accompanying drawing, the 10 simplicity of the device, as well as the advantage thereof will, it is thought, be perfectly apparent to those skilled in the art to which such invention appertains without further detailed description.

15 Having thus described the invention, what I claim is:

A metal tie for railway rails designed to have its lower portion embedded in concrete, including a member, the sides of which converge upwardly and the ends of which, at 20 the bottom of the said tie, being projected, the top of the tie, at the upper corners thereof, being integrally formed with overlying lips providing rail base engaging members, and straight seats for the rails be-

low the said lips, the said top of the tie adjacent the rail seats, having dove-tailed recesses, rail clamping plates having dove-tailed base portions received in the said recesses, each of said plates having a rail engaging extension overlying the rail seat designed to engage with a rail when arranged on the seat, said extensions, at the juncture with the body portions of the clamping plates having a downwardly inclined opening and the rail, below the said seat having a similar opening communicating with the end thereof, a headed member having its shank passing through the alining openings, and its threaded end projecting beyond the end of the tie, a washer member on said bolt, and a nut screwed on said bolt and contacting with said washer.

30 35 In testimony whereof I affix my signature in presence of two witnesses.

WILLIAM WILEY PLOWMAN.
